UNITED STATES PATENT OFFICE.

SPENCER C. CARY, OF NEW YORK, N. Y.

DESIGN FOR A HINGE-LINK.

SPECIFICATION forming part of Design No. 31,188, dated July 11, 1899.

Application filed June 13, 1899. Serial No. 720,417. Term of patent 14 years.

To all whom it may concern:

Be it known that I, SPENCER C. CARY, a citizen of the United States, and a resident of New York, borough of Brooklyn, in the county of Kings and State of New York, have invented and produced a certain new and useful Design for Hinge-Links, of which the following is a specification, reference being had to the accompanying drawing, forming part of the same, in which—

The single figure is a perspective view of my newly-designed hinge-link.

This link consists of two sides adapted to be inclosed by sleeves of hinge-leaves, portions connecting those sides, and parts extending away from and out of the line of one of those sides—for instance, the sides $s s' s^2$, the joining portions $j j'$, and the projections $p p'$.

The main features of the design are the sub-

stantially straight sides, such as s , the joining portions, such as $j j'$, one at each "end," so called, of the straight portion, other sides, such as $s' s^2$, really continuations of the piece brought again into line parallel with the side s , and projections, such as $p p'$, being parts of the sides $s' s^2$ turned away from those sides.

What I claim, and desire to secure by Letters Patent, is—

The design for a hinge-link substantially as shown and described.

Signed at New York, in the county of New York and State of New York, this 31st day of May, A. D. 1899.

SPENCER C. CARY.
